UNITED STATES PATENT OFFICE.

BENJAMIN WEXLER, OF BROOKLYN, NEW YORK, ASSIGNOR TO THE PEELLE COMPANY, A CORPORATION OF NEW YORK.

ELEVATOR-DOOR.

1,381,261.

Specification of Letters Patent. Patented June 14, 1921.

Application filed August 24, 1917. Serial No. 187,953.

To all whom it may concern:

Be it known that I, BENJAMIN WEXLER, a citizen of the United States, residing at the borough of Brooklyn, city of New York, county of Kings, and State of New York, have invented certain new and useful Improvements in Elevator-Doors, of which the following is a specification, reference being had therein to the accompanying drawings, 10 which form a part thereof.

My invention relates to elevator doors and more particularly to a type of fireproof doors having a rigid frame with a corrugated or other metal sheathing within said frame.

Fireproof doors made of wood, sheathed with metal, are sufficiently rigid throughout, to resist displacement under blows when the door is closed; and under severe heat will 20 not warp in a manner to cause the door to bind upon the side rails or tracks or to present an opening adjacent the sill or lintel through which flames may escape from or into an elevator shaft to or from the floor 25 of a building. In a door having a metal frame carrying corrugated metal sheathing within same, which door is known generally as a corrugated metal door, the structure is sufficiently light to have a tendency to flex 30 under blows or the expansion co-efficient in the door is sufficiently great to cause a warping of the door in the event of fire.

To insure the proper degree of protection against fire by means of corrugated metal 35 doors, it is necessary to provide braces extending vertically of the door intermediate the side bars of the frame, and to so construct these braces that they will co-operate with means carried by the wall of the ele- 40 vator shaft or well in a manner to prevent the door bulging, inwardly of the shaft, intermediate the side bars, either from blows upon the door or as the result of high temperatures upon either side of the door. 45 Such braces are generally known in the trade as "binder bars."

By my present invention, I provide an elevator door of the corrugated metal type wherein the binder bar structure is so formed 50 as to minimize any tendency toward the jamming of the door by reason of side swaying or sagging at either side thereof or from the expansion of the metal of the door under

heat. This binder bar structure is so formed that when applied to the lower door it will 55 support the door when in its lowermost position to produce what is known as a "truckable door," whereby the stresses of a load passing from the sill of the doorway to an elevator car, will be transmitted to the well 60 of the elevator shaft and thus relieve the supporting chains from any stresses beyond the predetermined load of the door structure. When this binder bar structure is applied to the upper door, as well as to the lower door, 65 I utilize this structure to arrest downward movement of the upper door so that in the event of breakage of the suspension means connecting the two doors, neither door can fall within the well or shaft and the upper door 70 cannot descend to the sill in a manner to subject the lower door, and the supporting means therefor, to a sufficiently violent shock to displace both doors and cause them to drop within the shaft or well.

This structure will also have the effect of 75 facilitating the opening or closing of both doors and minimize any tendency toward the binding of the door by reason of side swaying thereof.

While in the accompanying drawings, I have shown this binder bar structure applied to both doors, a desirable factor of safety is presented in the door structure if it be applied to either door section, although, it 85 is essential in order to include in a door what is known as a "truckable" feature, to provide such a mechanism at the sill of the door opening.

The invention consists primarily in an 90 elevator door embodying therein a vertically slideable door section comprising a metal frame having a metal sheathing within same, a fitting secured to the elevator shaft below the sill of the door opening anti-friction rollers mounted and spaced apart in said fitting, a T-bar extending vertically between the horizontal frames of the door section, the flanges of said T-bar having a free running fit between said rollers, means projecting beyond said rollers between the flanges of said bar and the door, and supports carried by said fitting above said rollers, adapted to engage the top frame of said door section and sustain a load upon said 100 door section when it is in the fully open 105 door section when it is in the fully open

position, and in such other novel features of construction and combination of parts as are hereinafter set forth and described, and more particularly pointed out in the claims hereto appended.

Referring to the drawings,

Figure 1 is an elevation of a corrugated metal door embodying the binder structure of my invention on both sections thereof, said view being taken from within the elevator shaft or well, and each section being broken away to disclose the arrangement of parts at the sill and at the lintel of the door;

Fig. 2 is a vertical section adjacent the binder bar structure at the lintel of the door opening upon a larger scale;

Fig. 3 is a similar view adjacent the sill of the door opening;

Fig. 4 is a section through the door adjacent the sill; and

Fig. 5 is a view similar to Fig. 4 showing a modified form of the invention.

Like letters refer to like parts throughout the several views.

In the embodiment of the invention illustrated in the drawings, I have shown two counterbalanced door sections *a* and *b* connected by means of a suitable suspension chain or cable *c* on opposite sides thereof. Each of these door sections is composed of a rectangular frame composed of T-bars, there being secured within this frame a suitable corrugated metal sheathing. The frame of each door section is provided with suitable shoes adapted to coöperate with the tracks or rails *d* upon opposite sides of the door opening and extending above and below the door opening to sufficiently guide the door sections. This construction is old and well known in the art, and exemplifies the type of door to which my invention is particularly adapted. Mounted within the elevator shaft or well, immediately below the sill of the door opening is a fitting *e*, having mounted thereon anti-friction rollers *f*, the axes of which project inwardly of the shaft, said rollers being spaced apart to leave the required clearance between same.

The corrugations in a portion of the door *a*, are flattened, and secured to this flattened portion and to the top and bottom bars of the door frame by riveting or in any other desired manner is a T-bar *g* the flanges of which are adapted to pass between, and have a loose running fit with, the rollers *f*. Adjacent the rollers *f*, I provide means projecting beyond the periphery of said rollers respectively, and between the flanges of the binder bar *g* and the metal sheathing of the door, which means will prevent the door intermediate the rails or tracks *d* springing inwardly of the shaft away from the sill, either when the door is in the opened or in the closed position and at all points between

these two positions. In the form of the invention shown in Figs. 1 to 4 this means comprises rollers *h* of greater diameter than the rollers *f* and mounted upon the pivot supporting said last named rollers respectively. The diameter of the roller *h* is such as to engage the web of the T-bar *g* with a loose running fit, and these rollers must be capable of rotation independently of said rollers *f* to compensate for the variance in the diameters of the rollers *h* and the rollers *f*. To relieve the pivot supporting the rollers *f* and *h*, I provide the fitting *e* with supports *i* arranged above said rollers upon opposite sides thereof so that when the door *a* is in the lowermost position, the overhanging top bar thereof will engage said supports *i* and sustain the load of any vehicles passing thereover to the elevator car.

The lower bar of the frame of the section *a* is cut away to clear the fitting *e* and the parts carried thereby, to facilitate the mounting of the door. The supports *i* when the door is opened, relieve the suspension chains from all stresses in excess of the weight of the door section, which weight is essential to properly counterbalance the upper door section *b*.

The binder bar and sheathing may be made of stock rolled to form, or it may be built up in the manner shown in the drawings.

The construction of the upper door section *b* is similar to that of the section *a* heretofore described. A fitting *e'* positioned adjacent the lintel of the door opening carries rollers *f'* and *h'* corresponding to the rollers *f* and *h*; with the binder bar *g'* corresponding in construction and function with binder bar *g*.

The top bar of the door frame is cut away to facilitate the mounting of the binder bar in relation to said rollers, and afford clearance for the supports *i'* carried by the plate *e'*. A plate *j* is used to close this opening in the frame so that when the door section is in the closed position, said plate *j* will seat upon the supports *i'* and limit the extent of the downward movement of this section.

In the modification shown in Fig. 5, the construction of the two door sections *a* and *b* and their appurtenances is as heretofore described, this form of the invention differing from that shown in Figs. 1 to 4 in those details for retaining the binder bar in relation to the rollers, and in the construction and arrangement of the supports for limiting the movement of the respective door sections. In this form of the invention, the fitting *e* is provided with oppositely disposed rectangular brackets *k* having rollers *m* mounted between said brackets respectively and the fitting *e*. The brackets *k* are preferably cast integrally with the fitting *e* and the upper edge of said brackets is ex-

tended above the rollers m in a manner to receive the load of the door section and prevent its being applied to the said rollers.

The operation of the herein described elevator door is substantially as follows:—

Under normal circumstances, when the door is closed, the binder bars $g-g'$ will be positioned between each pair of rollers $f-f'$ respectively with the rollers $h-h'$ in substantial engagement with the web of said binder bar. When the bars are in this position, it will be observed, any warping of the bar or tilting as the result of any dissimilar movements of the sides of the door, will have no binding action at the rollers $f-f'$ or $h-h'$ since there is only lineal engagement between said rollers and said binder bar. When opening or closing the door, the binder bars $g-g'$ move upon the respective rollers $f-f'$ and $h-h'$ without any likelihood of there being such frictional resistance as will impede the free movement of the door. By using the rollers $f-f'$ a fairly close fit between same and the flanges on the binder bar, may be provided, merely allowing clearance to compensate for expansion of the binder bar itself under heat, which expansion will be very slight. By using independently rotatable rollers $h-h'$ acting upon the under side of the flanges in the binder bar, as well as upon the web of said bar, the flanges of said bar will not only be held in proper relation to the rollers $f-f'$ but the web itself will be suitably guided. At the same time, engagement of the underside of the flange of said bar by frictional engagement with said rollers $h-h'$ will cause said roller to turn freely and avoid such binding action as will interfere with the free movement of the door sections.

The binder bars $g-g'$ during the full movement of the door, as well as when the door is opened or closed, will remain in the operative relation to the rollers $f-f'$ and $h-h'$, thus preventing the movement of the door section away from the walls about the door opening.

When the door is opened to the full extent, the top bar of the section a will rest upon the supports i , with the upper face of said bar substantially spanning the gap between the door sill and the elevator car, thus permitting the passage of trucks to and from the car, as with the usual form of truckable door. The load of such trucks will be sustained above the rollers $f-f'-h-h'$ thus avoiding likelihood of the breakage of the pivots upon which said rollers are mounted. The supports $i-i'$ upon the fittings $e-e'$ are merely emergency appliances, so that in the event of the breakage of the suspension means, the section b cannot drop beyond the point where the top bar will engage these bars.

It will be noted that the fittings $e-e'$ and the parts supported thereby are identical,

thus standardizing the fittings of all parts of doors made in accordance with the invention.

The operation in the form of the invention shown in Fig. 5 differs from that heretofore described merely in the omission of the anti-friction features afforded by the use of the rollers $h-h'$, the inwardly projecting arm of the brackets h performing the function of said rollers without, however, guarding against binding at this point.

It is not my intention to limit the invention to the precise details of construction shown in the accompanying drawings, it being apparent that such may be varied without departing from the spirit and scope of the invention.

Having described the invention what I claim as new and desire to have protected by Letters Patent, is:—

1. An elevator door embodying therein a vertically slideable door section comprising a metal frame having a metal sheathing within same, a fitting secured to the elevator shaft below the sill of the door opening, anti-friction rollers mounted and spaced apart in said fitting, a T-bar extending vertically between the horizontal bars of the frame of said door section, the flanges of said T-bar having a free running fit between said rollers, means projecting beyond said rollers between the flanges of said T-bar and the door, and supports carried by said fitting above said rollers, adapted to engage the top frame of said door section and sustain a load upon said door section when it is in the fully open position.

2. An elevator door embodying therein a vertically slideable door section, comprising a metal frame having a metal sheathing within same, a fitting secured to the elevator shaft below the sill of the door opening, anti-friction rollers mounted and spaced apart in said fitting, a T-bar extending vertically between the horizontal bars of the frame of the door section, the flanges of said T-bar having a free running fit between said rollers, and anti-friction rollers mounted upon axes concentric with said first named anti-friction rollers, said last named rollers being of a diameter to project beyond the first named rollers between the flanges of said T-bar and the door section.

3. An elevator door embodying therein a vertically slideable door section comprising a metal frame having a metal sheathing within same, a fitting secured to the elevator shaft below the sill of the door opening, anti-friction rollers mounted and spaced apart in said fitting, a T-bar extending vertically between the horizontal bars of the frame of the door section, the flanges of said T-bar having a free running fit between said rollers, anti-friction rollers mounted upon axes concentric with said first named anti-

friction rollers, said last named rollers being of a diameter to project beyond the first named rollers between the flanges of said T-bar and the door section, and supports on 5 said fitting projecting within the elevator shaft below and adjacent the sill of the door opening and above and on opposite sides of said rollers, whereby when the door section is fully open, the top bar thereof will engage 10 said supports and sustain a load upon said door section.

4. An elevator door embodying therein two counterbalanced door sections movable vertically in opposite directions in the same 15 plane, flexible connections between said door sections, tracks or rails guiding the movement of said door sections respectively, fittings secured to the elevator shaft below the sill and above the lintel of the door opening 20 respectively, each of said fittings having anti-friction rollers mounted and spaced apart therein, a T-bar extending vertically between the horizontal frames of each of said door sections, the flanges of said T-bars 25 respectively having a free running fit between the rollers adjacent the sill and adjacent the lintel of the door opening, means carried by said fittings respectively projecting beyond said rollers between the flanges of 30 said bar and the door, and supports carried by said fittings respectively above said rollers, adapted to engage the top bars of the frame of said section when it is in the fully open 35 position and limit the downward movement of the upper door section.

5. An elevator door embodying therein two counterbalanced door sections movable vertically in opposite directions in the same plane, flexible connections between said door sections, tracks or rails guiding the movement of said door sections respectively, fittings secured to the elevator shaft below the sill and above the lintel of the door opening, 40 respectively, each of said fittings having anti-friction rollers mounted and spaced apart therein, a T-bar extending vertically between the horizontal frames of each of said door sections, the flanges of said T-bars 45 respectively having a free running fit between the rollers adjacent the sill and adjacent the lintel of the door opening, and anti-friction rollers mounted upon axes concentric with said first named anti-friction rollers respectively, said last 50 rollers being of a diameter to project beyond said first named rollers between the flanges of each of said T-bars and its door section.

6. An elevator door embodying therein two counterbalanced door sections movable 60 vertically in opposite directions in the same plane, flexible connections between said door sections, tracks or rails guiding the movement of said door sections respectively, fittings secured to the elevator shaft below the 65 sill and above the lintel of the door opening, respectively, each of said fittings having anti-friction rollers mounted and spaced apart therein, a T-bar extending vertically between the horizontal frames of each of 70 said door sections, the flanges of said T-bars respectively having a free running fit between the rollers adjacent the sill and adjacent the lintel of the door opening, anti-friction 75 rollers mounted upon axes concentric with said first named anti-friction rollers respectively, said last named rollers being of a diameter to project beyond said first named rollers between the flanges of each of said T-bars and 80 its door section, and supports on each of said fittings projecting respectively within the elevator shaft below and adjacent the sill of the door opening, and above and adjacent the lintel of the door opening, said supports 85 being positioned above and on opposite sides of said rollers, whereby, when the door is in the fully open position, the supports adjacent the sill of the door opening will engage the top bar of the frame of the lower 90 door section and sustain the load thereon, and whereby the supports upon the fitting adjacent the lintel of the door will limit the downward movement of the upper door section. 95

7. An elevator door embodying therein a vertically slidable door section comprising a metal frame having a metal sheathing within same, a T-bar extending vertically between the horizontal bars of the frame 100 of said door section, a fitting secured to the elevator shaft below the sill of the door opening and rollers carried by said fitting projecting between the flanges of said T-bar and the door whereby said door will be held 105 against displacement from the door opening and binding between said T-bar and its coöperating means is prevented.

In witness whereof, I hereunto affix my signature, in the presence of two subscribing witnesses, this 23rd day of August, 1917.

BENJAMIN WEXLER.
